No. 811,192.

Specification of Letters Patent.

Patented Jan. 30, 1906.

Application filed November 20, 1901. Serial No. 83,210.

To all whom it may concern:

Be it known that I, FREEMAN R. WILLSON, Jr., a citizen of the United States, residing at Columbus, in the county of Franklin and 5 State of Ohio, have invented certain new and useful Improvements in Separators, of which the following is a specification, reference being had therein to the accompanying drawings.

10 This apparatus is designed for use in separating and screening reduced or partially-reduced material of various kinds—such as cement, ores, sand, clay, coke, or the like—whereby it may be separated into masses of 15 particles of various degrees of fineness and discharged into separate receptacles.

The apparatus consists in an inclosing framework, a series of superposed screens within said framework, and clothed with 20 screen material of decreasing fineness of mesh from the upper toward the lower screen and coupled centrally by flexible and yieldable connecting means and with the ends of the screen-frames free or “floating” and adapted 25 to impact against fixed stops or abutments on the framework and supported against downward and forward movement by stay-rods connecting them to the framework, and with endless traveling slatted conveyer-belts 30 arranged between the screens and adapted to receive the material passing through the screens and deliver it upon the “head” end of the next screen below, and in a system of independent chutes, whereby the product of 35 the different screens may be discharged into separate receptacles, all as hereinafter more fully described and set forth.

40 The framework and screens may be of any required size or capacity and any required 40 number of the screens and conveyer-belts may be employed; but for the purpose of illustration I have shown in the drawings 45 illustrative of the invention a series of four screens and the accompanying series of alternating endless conveyer-belts.

In the drawings, Figure 1 is a longitudinal 50 sectional elevation. Fig. 2 is an enlarged detail of the screen-vibrating mechanism. Fig. 3 is a side elevation of the apparatus complete. Fig. 4 is an enlarged detail of one of the screens and one of the conveyer-belts. 55 Figs. 5 and 6 are detached views of the idler-brackets. Fig. 7 is an enlarged cross-section on the line $x-x$ of Fig. 1. Fig. 8 is an en-

larged detail, partially in section, of the feed 55 mechanism. Fig. 9 is an enlarged detail view of a section of the side of the apparatus, illustrating the construction of the adjustments more fully. Fig. 10 is a plan view of the discharge-conveyers. Fig. 11 is an end 60 elevation. Fig. 12 is an enlarged detail of one of the conveyer-belts and its attachments. Figs. 13, 14, 15, 16, 17, and 18 are details of the conveyer-belt brackets. Fig. 19 is a plan view of the upper screen-frame detached, and 65 Fig. 20 is an end view of the same. Fig. 21 is a longitudinal section on the line $y-y$ of Fig. 19. Fig. 22 is a side view of one of the yieldable screen side bars detached. Fig. 23 is a sectional detail of the feed end of one of the 70 intermediate screens. Fig. 24 is an enlarged longitudinal section of a portion of one of the slatted conveyer-belts, and Fig. 25 is a plan view of the same.

Like letters of reference designate corresponding parts in all the figures.

The supporting-framework is designated at A, and within this framework is arranged an inclosing casing B for the alternating screens and conveyer-belts, as shown. The series of 80 screen-frames are designated as a whole at C C' C² C³, and the alternating conveyer-belts are designated as a whole at D D' D². The screens and belts being set at a relatively steep incline, the casing B is constructed to 85 conform in outline to the “nest” of screens and belts, as shown. The casing B is thus in the form of a box nearly square and set in a tilted-up position, with the feed mechanism at the upper corner, as shown as a whole 90 at B'.

The screen-frames are all substantially alike, and the description of one will suffice for all, the only difference being that the upper screen-frame has a wider imperforate 95 feed-plate than the remaining frames, as the upper frame receives the whole mass of the material from the feed mechanism, while the remaining screens receive only what passes through the next screen above. The screen-frames consist of two parts—the screen-frame proper, to which the screen material is secured, and a supporting-framework, with which the former is removably connected—so that screens of various degrees of fineness 100 may be employed in the same machine. The first part consists of transverse end bars c c', side bars c² c³, and intermediate longitudinal

supporting-ribs c^4 , as shown more clearly in Figs. 19, 20, and 21, which represent one of these screen-frames detached. The second part of the screen-frame consists of transverse end bars $c^6 c^7$, side bars $c^8 c^9$, the ends of the end bars projecting beyond the side bars, as shown at c^{10} , the side bars $c^8 c^9$ projecting above the bars $c^2 c^3$, as shown, to form the sides of the screen-trough. The two sets of bars $c^6 c^7$ and $c^8 c^9$ are strengthened by corner-braces r^{11} , and the bars $c c'$ and $c^2 c^3$ are likewise supported by corner-brackets c^{12} , as shown. The screen material is designated at c^{13} in Figs. 1 and 7, but is not shown in Figs. 19 and 21, as its presence would obscure the outlines of the framework and as its manner of attachment is so well known as not to need further illustration. The upper screen-material-supporting frame will rest upon the lower frame, with the end bars $c c'$ upon the end bars $c^6 c^7$ and with the side bars $c^2 c^3$ parallel to the side bars $c^8 c^9$. Any suitable means may be employed for retaining the upper frame removably upon the lower frame, and for the purpose of illustration I have shown two simple means for accomplishing this purpose. In Fig. 1 this supporting means is a rabbet c^{14} in the bars c' , while in Figs. 19, 20, and 21 small clips c^{15} are shown for the same purpose, the clips being attached to the end bars c' and embracing the lower and upper sides of the bars c' . The bars c are held in contact with the bars c^6 by locking-clips c^{16} , as shown in Figs. 21 and 23, which are easily removable to enable the screens to be changed when required. At the upper end of the upper screen is secured an imperforate feed-plate c^{17} , wide enough to project beneath the feed mechanism and upon which the material falls from the feed mechanism, as hereinafter described. The side bars $c^8 c^9$ of the upper screens are extended at the front or head end, as shown at c^{18} , to form the ends of the feed-plate, as shown. The lower screens are each provided with a similar feed-receptacle c^{19} , which is narrower than the one on the upper screen, as before stated, as they receive only a portion of the material, while the upper feed-plate receives all the material. The lower or "tail" edge of the plate c^{17} is turned upward for a short distance, as shown at c^{20} , to act as a retarder to the flow of the material, so that it will not pass to the screen-surface c^{13} too rapidly, but will be held back somewhat and caused to flow with greater uniformity upon the screen-surface. Extending between the projecting ends c^{10} of the end bars c' are side bars $c^{21} c^{22}$, attached to the extended ends by straps c^{23} and suitable bolts. At their centers each of the bars $c^{21} c^{22}$ is provided with a bearing c^{24} for the connection of the coupling-bars $c^{25} c^{26}$, one on each side, and between the bearings and the ends the bars $c^{21} c^{22}$ are cut away or reduced in size, as

shown, so as to transform the bars into "springs," as hereinafter more fully described. The ends of the side bars are cut away on their lower parts, as shown at c^{27} , so that they contact at their upper parts only 70 with the parts c^{10} , as shown, thus preventing any cramping between the parts c^{10} and $c^{21} c^{22}$ when the side bars yield under operation.

Mounted in bearings E in the lower left-hand corner of the framework A is a transverse shaft E', having eccentrics $e e'$ on its ends, each eccentric having a strap $e^3 e^4$ and rods $e^5 e^6$, each rod pivotally connected, respectively, to the lower ends of the coupling-bars $c^{25} c^{26}$, as shown. By this means when 80 the shaft E' is rapidly revolved the eccentrics by their connection to the coupling-bars will cause the screen-frames to be rapidly agitated in unison in lines at right angles to the surface of the screen material and likewise at right angles to the flow of the material over the screens.

The extended ends c^{10} of the end bars $c^6 c^7$ project through elongated openings c^{28} in the casing B, and the spring side bars $c^{21} c^{22}$ and 90 the coupling-bars $c^{25} c^{26}$ are connected outside the casing, as shown.

Opposite the upper or feed ends of the screen-frames are secured brackets F F' F² F³, one for each screen-frame and one set on 95 each side in opposite relations. These brackets are formed with projecting ends $f f'$ to form bearings for the reception of screw-rods $f^2 f^3$, each pair of screw-rods being set with the inner ends projecting toward one of the 100 extended ends c^{10} of the bars c^6 and each screw-rod provided with an enlargement f^5 on its inner end, as shown. Thus as the screen-frames are rapidly vibrated the ends c^{10} impact against the enlargement f^5 and 105 produce a severe "knocking" effect upon the screen-frames. The rods $f^2 f^3$, being screw-rods, are readily adjustable to regulate the distances between the enlargements f^5 and the ends c^{10} , so as to regulate the force of the 110 blows to which the screen-frames are subjected. Each screw-rod will be provided with a jam-nut f^6 to serve to lock the screw-rods in place when adjusted. Opposite the lower or 115 tail ends of the screen-frames are secured brackets F⁴ F⁵ F⁶ F⁷, each with projecting ends $f^7 f^8$ and with adjusting screw-rods f^9 120 f^{10} , enlargements f^{11} , and jam-nuts f^{12} , similar to and for the same purpose as the analogous parts at the feed ends of the screens. 125 The screens are thus actuated only at their centers and are free or floating at their ends, being limited in their motion by the "abutments" f^5 and f^{11} , between which they move, as shown. Wear-plates f^{13} will be attached 130 to the parts c^{10} where they engage the enlargements $f^5 f^{11}$ to prevent abrasion.

Tie-rods G will be connected flexibly by one end at g to the centers of the bars $c^{21} c^{22}$ and at the other end at g' to some fixed por- 130

tion of the framework or to eyes f^{14} on the brackets $F F' F^2 F^3$, as shown. The eyes f^{14} afford a convenient means for securing the upper or fixed ends of the rods G ; but they may be connected to any other stationary portion of the framework or its attachments, if preferred. By this means the screen-frames are all held in place and prevented from "dragging" downward against the lower sides of the lower set of openings c^8 , while at the same time being free to move between the stops $f^5 f^{11}$, as before described. This arrangement of the tie-rods G is an important feature of the invention, as they while firmly supporting the screens and preventing them from moving endwise in the framework and rubbing unnecessarily against the fixed parts of the apparatus at the same time the screens are held sufficiently loose to permit of the necessary vertical vibratory movement.

The endless conveyer-belts $D D' D^2$ are arranged beneath the screens $C C' C^2$; but no belt is employed beneath the lowermost screen, as the material passing through that screen falls upon the bottom B' of the casing B and is carried thence to a transverse trough b , containing a screw conveyer b' , by which the material falling therein is discharged at one side of the machine. The conveyer-belts are all alike, and each is connected and operated in the same manner, as shown. The belts each consist of an endless canvas strip d , running over rollers $d' d^2$ at the ends, the journals d^3 of the upper rollers d' being supported in bearings f^{16} on the brackets $F F' F^2$, while the journals d^4 of the rollers d^2 are supported in bearings f^{17} , slidably disposed in slots f^{18} in the brackets F^4, F^5 , and F^6 . The bearings f^{17} are each provided with a screw f^{19} and each screw connected by its inner end to its respective bearing f^{17} and each provided with a nut f^{20} outside the brackets $F^4 F^5 F^6$, by which means the tension of the canvas belts may be regulated. It will be readily understood by this construction that the belts may be drawn "taut" and the tension maintained as required by simply adjusting the nuts f^{20} upon the screw-rods f^{19} , and thereby drawing the bearings f^{19} and the rollers d^2 , carried by them, outward in the slots f^{18} . At intervals across the belts d are secured transverse strips or bars H , each strip being connected to the belt on the outer side of the latter, as shown, so as not to interfere with the running of the belt over the rollers $d' d^2$. At each end of each bar H is secured a plate h , (see Fig. 12, which represents a side view of one of these strips or bars and a cross-section of one of the belts,) and upon the outer end of each plate is formed a journal h^2 , carrying rollers h^3 , as shown. Attached to the inner surfaces of the casing B opposite the lower lines of the rollers h^3 are strips $h^4 h^5$, which form tracks for the rollers, as shown more clearly in Fig. 7, to afford supports for the

rollers and the strips or bars H and the belts d , carried thereby. By this means the belts and transverse strips are supported and prevented from sagging. The slatted belts will thus maintain their true parallel positions with relation to the screens at all points of their movements, and the transverse strips will prevent the belts from sagging under the weight of the material thereon.

Endless chains I are connected near the opposite sides of each of the endless belts, each chain being attached to each of the plates h at $i i'$, as shown in Figs. 7, 12, 24, and 25. I have shown in the drawings the ordinary detachable chains for the purpose of actuating the endless belts with wings or lugs where they are to be attached to the plates h and belts d . At the ends of the rollers $d' d^2$ in line with the chain I and connected to revolve with the rollers are a series of sprocket-wheels i^2 , over which the chains run, the chains and the bars H thus serving to bear the heavy strains, leaving the canvas belt to support the weight of the load only between the cross-bars.

The upper rollers d^3 come beyond the lines of the screens or outside of both their head or feed ends, and the lower rollers d^2 also extend beyond the tail or discharge ends of the screen, so that all the material which passes through the screens will fall upon the belt below it, and as the belt travels upward the material will be carried upward and delivered upon the feed-plate c^{19} of the next screen below, and so on throughout the series, so that all the material passing through each screen is caught and delivered to the head end of the next screen below by the traveling slatted belts and the final result delivered to the trough b and conveyer b' , as before stated.

In the lower part of the framework B are arranged a series of troughs $b^2 b^3 b^4 b^5$, corresponding to and in parallel relations to the trough b and provided, respectively, with screw conveyers $b^6 b^7 b^8 b^9$, similar to and in line with the conveyer b' , as shown. Each of the troughs $b^2 b^3 b^4 b^5$ is disposed to receive the tailings from one of the screens, while the trough b , as before stated, receives the product from the lower screen. The tailings from the screens are guided into the respective troughs by gather-boards $b^{10} b^{11} b^{12} b^{13} b^{14}$, as shown in Fig. 1. Thus the product of each screen is kept separate and discharged by a separate screw conveyer and as many distinct separations made as there are screens. Thus by providing the screen-frames with screen material of increasing degree of fineness from the upper to the lower screen the material will be divided into a series of masses of correspondingly-increasing fineness.

The feed mechanism consists in a circular casing J , containing a screw conveyer j , mounted upon a shaft j' , journaled by its ends

in the housing j^2 . The casing J is formed with a recess j^3 on one side, through which the material is discharged by the revolution of the conveyer and fed in a uniform stream to the receiving-plate c^7 of the upper screen. The material is fed through a hopper j^4 .

Motion is imparted to the various moving parts from the main drive-shaft E' in the following manner: On one end of the shaft E' is 10 a belt-pulley K , by which motion is imparted to the shaft from the source of power, and on the opposite end of the shaft is a belt-pulley k , from which a belt K' leads to a larger belt-pulley K^2 on the shaft j' of the screw conveyer 15 j , by which motion is imparted to the latter, the belt K' being twisted to cause the conveyer j to travel in the proper direction. L is a counter-shaft journaled in adjustable sliding bearings L' on the framework A and 20 provided with a comparatively large chain or sprocket wheel L^2 , connected by a chain L^3 to a smaller chain or sprocket pinion L^4 on the shaft E' , by which a comparatively slow motion is imparted to the shaft L . The bearings L' are slidably disposed upon a base-frame L^5 and rendered adjustable by set-screws L^6 , as shown, to produce the proper tension on the chain-belts. Upon one end of 25 the counter-shaft L is a sprocket-pinion L^7 , and on the corresponding ends of the shafts of all the conveyers b' b^6 b^7 b^8 b^9 are mounted corresponding sprocket-pinions b^{10} b^{11} b^{12} b^{13} b^{14} , all in alinement with each other and also 30 with the pinion L^7 , so that a single chain L^8 35 will engage all the sprocket-wheels, as shown in Figs. 1 and 3. The chain L^8 is arranged to engage the pinions b^{10} b^{11} b^{12} b^{13} b^{14} alternately above and below them, as shown. Hence it is necessary to arrange the conveyers alternately right and left handed in order that 40 they will discharge all at one side.

The conveyers b' b^6 b^7 b^8 b^9 are shown in Figs. 9 and 10 supported at their discharge ends by hangers b^{15} b^{16} b^{17} b^{18} b^{19} , so that the 45 material will pass out beneath the hangers.

The distance between the shaft L and the sprocket-wheels b^{10} b^{11} b^{12} b^{13} b^{14} being considerable, the chain L^8 will require suitable supports to prevent undue sagging, and such 50 supports are shown in Figs. 3, 5, and 6 consisting of idler-sprockets L^9 L^{10} , supported in yoke-frames L^{11} L^{12} , each yoke-frame adjustably supported by screws L^{13} L^{14} in standards L^{15} L^{16} , as shown, so that the tension of the 55 chain may be readily and easily regulated. One of the idler-pinions L^9 will thus be arranged to regulate the tension of the upper side of the chain L^8 , and the other idler L^{10} will be similarly arranged to regulate the tension of the lower side of the chain, as shown.

The upper shaft d^3 of the lower endless belt D^2 is provided with a sprocket-pinion M , to which a chain m leads from a somewhat smaller sprocket-pinion m' on the shaft L ,

and upon the opposite end of the same shaft d^3 of the upper roller of the lower endless belt another sprocket-wheel m^2 is mounted and connected by a chain m^3 to another sprocket-wheel m^4 on one end of the shaft d^3 of the upper roller of the central endless belt. On the 70 opposite end of the same shaft of the central belt is another sprocket-wheel m^5 , connected by a chain m^6 to a sprocket-wheel m^7 on the shaft d^3 of the upper roller of the upper endless belt.

The shaft L , with its sprockets, operates as the primary driving device for driving all the conveyers, the other driving devices being secondary and arranged some on one side of the machine and some on the other, so that the 80 conveyers will all be driven in the proper direction, the power for driving the entire mechanism being applied through one shaft E' .

It will be seen that peculiar effects result from combining with the series of superposed screens the series of sustaining rods or links G when the latter are arranged in the way shown and described. These links being approximately parallel to the screens, the latter are permitted to freely vibrate, and as 90 the screens are inclined these sustaining rods or links act in opposition to the parts e^8 c^{25} to hold all the moving structure in its proper position. If the sustaining links or rods g were more nearly vertically arranged, they 95 would tend to interfere with the free vibratory movement of the screens, but arranged as they are in conjunction with the reciprocating actuating devices they insure that all the screens shall have a free floating movement from end to end of each in contradistinction from screens which have their ends held in fixed positions by sustaining devices. These links or rods g are connected to the screens at the centers, and therefore do not 100 interfere with the said free floating movement of the ends. When screening devices are held stationarily at the ends and only vibrate at the center parts, the sieving efficiency is greatly reduced; but with mechanism of the character of the present one the screening-work is accomplished throughout the whole length of the screens approximately uniformly, the end parts being as efficient in sieving the ores, cement, sand, or other reduced material as are the portions at the 105 centers.

What I claim is—

1. In a screening mechanism for ore or similar materials, the combination of the series of inclined superposed screens, the longitudinally - reciprocating actuating devices pivotally connected to and arranged to support each screen of said series near its center, the ends of each screen being free to vibrate 110 about the axis of the screen's pivotal connection with said reciprocating device independent of the vibration of the ends of any other 115

screen of the series, and the series of vibrating sustaining devices, each pivotally connected to the central part of one of said screens and also connected to a relatively 5 stationary support, substantially as set forth.

2. In a mechanism for screening ores or other material, the combination of the series of inclined superposed screens, the pair of longitudinally - reciprocating actuating devices arranged one at either side of said series of screens and pivotally connected to each screen of said series near its center, the ends of each screen being free to vibrate about the axis of its pivotal connection with said reciprocating device independent of the vibration of the ends of any other screen of the series, said reciprocating actuating device being arranged to bodily reciprocate said series of screens in planes at an angle to the planes of the flow of material along the screens and the series of vibrating sustaining devices each flexibly connected to one of said screens and also connected to a relatively stationary support, substantially as set forth.

25 3. In a mechanism for screening ores and other material, the combination of the series of inclined superposed screens, each free at its ends to permit vertical vibration thereof, a longitudinally - reciprocating bar connecting the screens of the said series and adapted to bodily reciprocate the said series of screens, a main frame, a series of vibrating links or rods pivotally connected to the main frame and each pivotally connected to one of the 35 screens near its center, substantially as set forth.

4. In a mechanism for screening ores or like material, the combination of the main frame, the series of inclined screens, each free 40 at its end for vertical vibration, the reciprocating mechanism connected flexibly to the central parts of the screens respectively and adapted to bodily reciprocate the said series of screens, and the sustaining bars or rods 45 pivotally connected to the main frame and pivotally connected to the central part of the screens respectively and situated approximately parallel to the screens, substantially as set forth.

50 5. In a screening mechanism for ores and like material, the combination of a series of inclined superposed screens, the power-shaft arranged beneath said series of screens, the bars connected to each screen of the series 55 near its longitudinal center, means interposed between said power-shaft and said bars for reciprocating the bars and the screens connected thereto, and means for sustaining said series of screens from downward movement about the axis of said power-shaft beyond a predetermined limit and arranged substantially as set forth to permit the free

vibration of the screens bodily without resistance from said sustaining means.

6. In a mechanism for screening ores or like material, the combination of the main frame, the series of inclined superposed screens, each free at its ends for vertical vibration, the bars arranged at either side of said series of screens and pivotally connected to each screen of the 65 series near its center, the power-shaft arranged beneath the lowermost screen of the series, power - transmitting devices interposed between said power - shaft and the lower ends of said bars for reciprocating the 70 bars and the screens connected thereto, and the sustaining-links pivotally connected to the main frame, and each pivotally connected to one of the said screens near its center and arranged to permit the free vibration of 75 the series of screens bodily while preventing its downward movement about the axis of said power - shaft beyond a predetermined limit.

7. In a mechanism for screening ores and similar material, the combination of a series of inclined superposed screens, each free at its ends to permit vertical vibration thereof, a reciprocating actuating mechanism connected to the central part of each screen of the 80 series, and a series of endless conveyers, each conveyer being arranged under one of the said inclined screens and adapted to carry upward the material passing through it and deliver it to the upper end of the screen passing 85 below the conveyer, substantially as set forth.

8. In a mechanism for screening ore and similar material, the combination of the main frame, the casing, the supplemental 90 frame secured to the main frame and arranged therein at an inclination substantially as set forth, a series of reciprocating screens in the said supplemental frame and casing inclined substantially as set forth, an actuating mechanism connected with each screen of the said series at the central part thereof and situated outside the said casing, the sustaining devices for the screens pivotally connected to the said framework and also pivotally connected to the central parts of the screens respectively, and the series of endless conveyers in the said supplemental frame and housing, each arranged between a screen and an adjacent one and adapted to carry 95 the material passing through the upper screen and deliver it to the upper end of the lower one, substantially as set forth.

In testimony whereof I affix my signature in presence of two witnesses.

FREEMAN R. WILLSON, JR.
